UNITED STATES PATENT OFFICE

GUSTAV VON DEN STEINEN, OF CLEVELAND HEIGHTS, OHIO, ASSIGNOR TO THE GLASCOTE COMPANY, OF EUCLID, OHIO, A CORPORATION OF OHIO

APPARATUS FOR MAKING GLASS-COATED PIPE COILS

Application filed December 14, 1928. Serial No. 326,027.

This invention relates generally to the application of vitreous or fused coatings to articles, and has particular reference to apparatus for making pipe coils having such coatings.

In coating a coil or other article with glass it is customary to apply the coating material in the form of a powder, and then heat the article in a furnace to approximately 1800° F., at which temperature the powder is fused and converted into an impervious coating. At this temperature steel and other available metals become so soft that it is a difficult problem to support a coil during the coating process so as to prevent the convolutions of the coil from being distorted and warped.

It is the object of this invention to provide a novel form of apparatus for producing glass-coated pipe coils which will have the desired shape and not be distorted and warped.

Other objects and advantages of this invention will be apparent from the following description taken in connection with the accompanying drawings, of which

Fig. 1 is a plan view of my coil supporting apparatus showing a coil supported therein;

Fig. 2 is a sectional view on line 2—2 of the apparatus shown in Fig. 1;

Fig. 3 is a sectional view of the coil taken on line 3—3 of Fig. 2;

Fig. 4 is a detail section, taken on line 4—4 of Fig. 2, showing the upper portion of the central column of the coil;

Fig. 5 is a detail elevation showing one of the coil supporting rods;

Fig. 6 is a cross-section, taken on line 6—6 of Fig. 5, showing one of the coil supporting nipples; and

Fig. 7 is an elevation showing a plug for closing the supporting nipples.

Referring now in detail to the drawings of which Figs. 1 and 2 show a coil 10 prepared for coating and supported within a framework indicated generally at 11. It should be understood that the work supporting apparatus of my invention may be used in connection with pipe coils of various shapes and forms, but the coil shown in this instance is formed from two lengths of pipe

bent to helical form, as indicated at 12 and 13, and arranged so that the convolutions of one helix alternate with the convolutions of the other helix, thus providing two separate paths of flow through the coil. To admit fluid to coil 10 I provide a central tubular column 14 extending coaxially with the coil and having the lower ends of helical coils 12 and 13 connected thereto adjacent its lower end at points 180° apart. The lower end of column 14 is closed, while at its upper end a threaded pipe nipple 15 is concentrically attached thereto, as by welding, to provide a suitable connection for a fluid supply line and also to provide a rigid connection for centrally supporting the coil during the coating process, as will be more fully disclosed hereinafter. The upper ends of helical coils 12 and 13 are connected at points 180° apart, as shown in Fig. 4, to a discharge fitting 16, which I prefer to construct in the form of a sleeve, arranged concentrically with column 14 and welded to the upper portion thereof. The diameter of sleeve 16 is materially larger than the diameter of column 14 and of the supply pipe leading to column 14, so that the space 17, between sleeve 16 and the supply pipe, will serve as a discharge passage for coil 10. To facilitate the welding of sleeve 16 to column 14 the wall of the lower end portion 16' of sleeve 16 is flanged or bent inwardly to circumferentially engage column 14, while at the opposite end of sleeve 16 I provide an annular enlarged portion 18, by which the coil may be attached to the apparatus with which it is to be used and to which a discharge connection may be conveniently applied.

For rigidly supporting the coil during the coating process I provide the framework 11, composed of members welded or otherwise securely fastened together to form a base portion 19, having uprights 20 upon which an annular member 21 is mounted. A cross-beam 22 extends diametrically across annular member 21 and carries a tubular projection 23 welded thereto from which coil 10 is suspended with its axis in alignment with the axis of the projection. Adjacent its free end projection 23 carries a removable pin 24

which extends diametrically through the walls of the projection. In order to support the coil centrally a piece of pipe 25 is connected to the nipple 15 carried by column 14 by means of a pipe coupling 26. When the 5 upper end of pipe 25 is slipped over projection 23 perforations provided in pipe 25 register with the perforations of the projection so as to admit the pin 24 which couples the 10 parts together.

For supporting the coil about its perimeter I provide a carrier which includes a flanged coil supporting member or ring 27 to which the coil is connected at spaced points 15 about the perimeter of the coil. This supporting ring 27 is carried by a central hub 28 to which it is connected by bars 29 extending radially outwardly from the hub and having at their outer ends hooks 30 which 20 engage the lower flange of ring 27 and are welded thereto. The hub 28 is of suitable diameter to permit it to be slipped over pipe 25 and is provided with aligned slots 31 which register with the perforations of pipe 25 and of projection 23 to receive pin 24 upon 25 which the hub is supported. At the top of the coil, at points spaced about its perimeter, I provide internally threaded nipples 32 which are welded to the convolutions at one 30 end of the coil, as shown in Figs. 2 and 5. Supporting rods 33 are provided for connecting the coil to supporting ring 27 and have one end threaded and screwed into nipples 32. At their opposite ends rods 33 are 35 welded to ring 27 and to the hooks 30 of bars 29. Notches are cut in the lower flange of ring 27 to receive the rods 33 to permit them to be welded to the web of ring 27 along a portion of their length. To make the coil 40 a rigid unit and to prevent sagging and distortion of its convolutions, I weld spacers 34 between adjacent convolutions in rows aligned axially with the nipples 32. The column 14, which extends coaxially of the coil, connects and supports the end convolutions 45 thereof, and thus adds materially to the rigidity of the coil as a unit.

After the coil has been attached to the ring 27 and suspended from the frame 11, the 50 coating material is applied to the entire surface of the coil including the spacers 34, the nipples 32 and the column 14. The supporting frame and the suspended coil are then placed in a furnace which is brought to the 55 temperature necessary to fuse the coating material. After cooling, the coil is removed from the frame by withdrawing pin 24 and is disconnected from supporting ring 27 by cutting rods 33. The stub ends of rods 33 are 60 unscrewed from nipples 32, and plugs 35 are then screwed into these nipples and sealed with litharge or other suitable material.

When the supporting frame and the coil 65 are heated to the high temperature necessary to fuse the coating material, the metal of the

supporting frame loses its rigidity and its members tend to buckle and twist out of shape. However, by my method of constructing and uniformly supporting the coil as a substantially rigid unit, the distortion 70 and twisting of the members of the supporting frame can have no deleterious effect on the coil so long as the coil does not contact with the supporting frame. It will be seen 75 that I have provided an arrangement in which the coil is supported at its center and also at points around its perimeter so that each of the several convolutions of the coil is supported and rigidly held in properly spaced relation by the aligned spacers 34. The ring 27 which is heavy and rigid supports the coil evenly around its perimeter and prevents warping and distortion, while the column 14, connected to the projection 23, affords a central support and rigidly maintains the coil in proper alignment. 80

While I have referred, in this specification and also in the claims, to a glass-coated coil it will be understood that the invention is not limited to coatings that come within the technical term "glass". I use the term "glass-coated" in the broader sense in which it means any vitreous or fused coating. 85

It is also to be understood that I do not limit my invention to the particular form of coil and coil supporting means herein shown and described, since these forms are illustrative only, but regard my invention as including such forms as fall within the scope 90 of the appended claims. 100

Having thus described my invention, what I claim is:

1. In apparatus for glass-coating a pipe coil of the type having a plurality of convolutions, the combination of, a frame, and means for supporting the coil in said frame while it is being treated, said means comprising a substantially rigid carrier having supporting connection with said coil at a plurality of points in alignment with the convolutions of the coil, and means for supporting the carrier substantially centrally thereof on the frame. 105

2. In apparatus for glass-coating a pipe coil of the type having a plurality of convolutions and a central column, the combination of, a frame, means carried by said frame for supporting the coil out of contact with the frame while it is being treated, said means having supporting connection with the central column and with the convolutions of said coil. 110

3. In apparatus for glass-coating a pipe coil of the type having a plurality of convolutions and a central column, the combination of, a frame, a coil supporting member on said frame, said member having supporting connection with said column, and means carried by said member having supporting 115 120 125 130 135

connection with one end of the coil in alignment with the convolutions thereof.

4. In apparatus for glass-coating a pipe coil of the type having a plurality of convolutions and a central column, the combination of, a frame, means carried by said frame for supporting the coil with its column in substantially vertical position while the coil is being treated, said means comprising a member having supporting connection with said column and adapted to prevent lateral deflection thereof, and an annular member having supporting connection with one end of the coil in alignment with the convolutions thereof.

5. In apparatus for glass-coating a pipe coil of the type having a plurality of convolutions with spacers between adjacent convolutions, the combination of, a frame, and means on said frame for supporting the coil out of contact with the frame while it is being treated, said means having supporting connection with one end of the coil in alignment with the spacers thereof.

6. In apparatus for glass-coating a pipe coil of the type having a central column and a plurality of convolutions with spacers therebetween, the combination of, a frame, a coil supporting member on said frame, said member having supporting connection with said column, and means carried by said member having supporting connection with the coil at points in alignment with said spacers.

7. In apparatus for glass-coating a pipe coil of the type having a plurality of convolutions, the combination of, a frame, and means for suspending the coil in said frame but out of contact therewith while it is being treated, said means comprising a member on said frame, a sleeve carried by said member, a plurality of arms extending laterally from said sleeve, an annular member supported by said arms, and means connecting said annular member with one end of said coil at a plurality of points in alignment with the convolutions of the coil.

8. In apparatus for glass-coating a pipe coil of the type having a central column and a plurality of convolutions, the combination of, a frame, and means for suspending the coil in said frame but out of contact therewith while it is being treated, said means comprising a member on said frame having supporting connection with said column, a sleeve carried by said member, a plurality of arms extending laterally from said sleeve, an annular member supported by said arms, and means connecting said annular member with one end of said coil at a plurality of points in alignment with the convolutions of the coil.

9. In coating apparatus of the character described, the combination of a frame having a supporting portion thereon, an annular article supporting element adapted for supporting connection at a plurality of points

with the article carried thereby, and means for removably suspending said element from said supporting portion, the last mentioned means including a part disposed substantially on the axis of said element and having releasable telescoping engagement with said supporting portion.

In testimony whereof, I hereunto affix my signature.

GUSTAV VON DEN STEINEN.
